UNITED STATES PATENT OFFICE.

JOHN B. LISCHKE, OF LANCASTER, KENTUCKY.

VAULT-DOOR SAFETY DEVICE.

Application filed June 16, 1927. Serial No. 129,336.

This invention relates to vault doors, and especially to an attachment therefor.

The principal object of the invention is to provide means by which a bank vault door, 5 or the like, may be locked in a partially open position and uncontrollable from the exterior of the vault.

Another object of the invention is to provide key lock controlled means by which a 10 bank vault door, or the like, may be locked in a partially open position and uncontrollable from the vault exterior by unauthorized persons.

Other objects of the invention are mentioned and described herein.

The preferred embodiment of the invention is illustrated in the accompanying drawing, wherein Figure 1 is a side view in elevation and in section illustrating a fragment 20 of a bank vault and door with my invention applied thereto; Fig. 2 is a front elevation thereof; and Fig. 3 is a bottom plan view illustrating the latch element broken away.

Similar numerals of reference indicate like 25 parts throughout the several views on the drawing.

Referring to the details of the drawing the numeral 1 indicates a fragment of a vault frame, or door jamb, and 2 the usual vault 30 door hinged thereto, the two elements being provided with the usual complementary stepped construction well known in the art.

My invention contemplates the use of a keeper 3 rigidly secured to a stepped portion 35 of the vault door and a lock controlled latch 4 pivotally mounted within the latch casing 5 which is secured to the face of the vault frame within the vault. The keeper 3 may be rigidly secured to the door by screws 6, 6 40 and may be provided with the latch aperture 7 adjacent the forward end thereof, said aperture being adapted to be engaged by the hook 8 of the latch when the latter is operable manually, or otherwise.

The casing 5 may be a box-like element 45 open at the bottom thereof to permit the downward swing of the latch element and may be provided with the top wall 9, inner end wall 10, two side walls 11, 11, and a front 50 wall 12, the latter of which may be upwardly extended at 13 to form an interior lock chamber 14, and all of said walls may be integral with each other. The casing 5 may be provided also with a pair of lateral, 55 opposed bracket elements 16, whereby it may be fastened to the vault frame 1 by screws 17.

The lock chamber 14 may be provided with a rear opening 18 to facilitate the mounting of the key lock 15 in the chamber 14, which opening may thereafter be closed by the 60 cover plate 19 removably secured over said opening by suitable screws 20.

A portion of the lock 15, which may be of any suitable bolt type, may project through the front wall 12 of the casing to admit the 65 key 22 for effecting vertical reciprocal action of the lock bolt 23.

The latch 4 may be pivotally mounted on the pin 24 within the casing and intermediate the latch extremities, the pin 24 being horizontally disposed and having its opposite ends mounted in the side walls 11 of the casing 5. The latch 4 is normally held depressed by a leaf spring 25 which may be secured to the upper face of the latch by a screw 28, the other end of said spring bearing resiliently against the inner face of the top wall of the casing 5. The latch 4 therefore, being resiliently and downwardly actuated by the spring 25 would cause the 70 hook 8 to automatically engage the keeper aperture 7 as the door 2 is swung inward.

The latch 4 may be provided with an extension 26 which bears against the lower end of the reciprocable lock bolt 23, the latter functioning as a stop element to limit the downward swing of the opposite end of said latch, said latch being provided also with a shoulder or abutment portion 27 which is engageable by the extreme outer end 75 of the keeper 3 when the hook 8 is in engagement with keeper aperture 7.

When the latch 4 is connected with keeper 3 the latch hook 8 prevents opening of the door 2 from the outside of the vault, and 80 the latch abutment 27, engageable by the end of the keeper 3, prevents closing of the door from the outside. But a person confined within the vault could readily disengage the latch from the keeper and emerge from 85 the vault if conditions exteriorly of the vault justify such action, and this disengagement can readily be effected by upward manual pressure on the under side of the latch 4 adjacent the hook section 8 thereof.

The latch 4 may be elevated and locked in inoperative position by downward actuation of the lock bolt 23, as indicated by the dotted line position of said latch, thereby rendering the device wholly inoperative and locking it 90 against use by an unauthorized person. An advantage of my safety device is that it can 95

readily be mounted, as an attachment, in combination with either the rectangular or square vault door.

If, through inadvertance, the vault door should become latched in the position illustrated in Fig. 1 and no person should be confined within the vault, a special tool (not shown) may be provided, whereby an authorized person may manually tilt the latch 4 upward to disengage the latch hook from the keeper. For night or holiday use the latch 4 may be locked in the inoperative position, as described.

I claim:

1. A device of the character described and including in combination, a vault door, a keeper thereon, a vault body element, a latch mount carried by the vault body element, a latch tiltably mounted upon said latch mount intermediate its extremities and adapted to cooperate with said keeper, and lock controlled means for tilting said latch.

2. A device of the character described and including in combination, a vault door, a keeper thereon, a vault body element, a spring actuated tilttable latch carried by said vault body and adapted to engage said keeper by action of said spring, and lock controlled means for tilting said latch out of engagement with said keeper.

3. A device of the character described and including in combination, a vault door, a keeper thereon, a vault body element, a latch housing mounted upon the vault body and provided with a bottom opening, a latch pivotally mounted in said housing and adapted to cooperate with said keeper through said housing bottom opening, and lock controlled means carried by said housing for actuating said latch.

4. A device of the character described and including in combination, a vault door, a keeper thereon, a vault body element, a latch mount carried by the vault body element, a latch tiltably mounted upon said latch mount intermediate its extremities and adapted to cooperate with said keeper, and lock controlled means engageable with one extremity of said latch for tilting the latter out of engagement with said keeper.

5. In a device of the character described, a latch housing, a latch pivotally mounted in said housing intermediate its extremities and provided with a hook at one end, and lock controlled means mounted in said housing and adapted to engage the opposite end of said latch for tilting the latter.

6. The combination with a vault door and door frame or jamb, of a keeper on said door, and means carried by said door frame or jamb for locking said door in ajar position, said means including a combined door stop and latch element pivotally mounted intermediate its extremities and adapted to automatically engage said keeper as the door is swung toward the door frame or jamb, and lock controlled means for retaining said stop and latch element in an inoperative position.

7. The combination with a vault door and door frame or jamb, of a keeper on said door, and means carried by said door frame or jamb for locking said door in ajar position, said means including a spring actuated combined door stop and latch element pivotally mounted intermediate its extremities and adapted to automatically engage said keeper as the door is swung toward the door jamb, said stop and latch element being manually disengageable from said keeper from within the vault, and lock controlled means for retaining said stop and latch element in an inoperative position.

8. A vault door safety device of the character described and comprising a housing, a combined stop and latch element pivotally mounted within said housing intermediate the extremities of the former, said stop and latch element including a hook at one end and an extension at the opposite end thereof, spring means for downwardly actuating the hook on said stop and latch element, and stop means to limit the downward movement of said hook, said means including an element comprised in a lock, the latter including means for retaining the stop and latch element in a retracted position.

9. A vault door safety device of the character described and comprising a housing provided with horizontal and upright connected chambers, a key lock in said upright chamber, a combined stop and latch element pivotally mounted in said horizontal housing chamber, said latch element being provided with a hook at one end and an extension on the opposite end thereof, a spring for actuating the hook of said stop and latch element, and a bolt in said lock for engaging the extension of the stop and latch element to retain same in a retracted position.

In witness whereof I have hereunto affixed my signature this 13th day of June, 1927.

JOHN B. LISCHKE.
